BROODER

Harvey L. Clark, Salem, Oreg.

Application January 6, 1944, Serial No. 517,243

1 Claim. (Cl. 119—33)

1

This invention relates to brooders.

An object of this invention is to provide a brooder having heat transfer means therein for absorbing and transferring the body heat of the chicks so as to simulate as closely as possible the body heat of the mother hen.

Another object of this invention is to provide a brooder of simple construction which can be readily cleaned, is of sturdy construction, and can be made at relatively small cost.

A further object of this invention is to provide a brooder for small chicks which will permit the chicks to enter the interior thereof from the sides.

A further object of this invention is to provide a brooder which comprises a housing having top and bottom walls, supporting posts for the top wall, felt side and end walls, copper plates secured to the inner sides of the top and bottom walls, felt coverings for the metal plates and depending felt strips.

To the foregoing objects and others which may hereinafter appear, the invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawing:

Figure 1 is an expanded perspective view of a brooder constructed according to an embodiment of this invention with portions cut away to show the details of construction;

Figure 2 is a fragmentary detail view of one of the corners showing the means for fastening the bottom and top parts of the brooder to each other;

Figure 3 is a fragmentary sectional view; and is taken on the line 3—3 of Figure 1.

Referring to the drawing the numeral 10 designates the top wall of a brooder housing which, in the present instances, is rectangular in plan and has secured thereto a plurality of upright supporting posts 11. The posts 11 are provided at their lower ends with downwardly opening sockets or recesses 13 within which positioning pins or dowels 14 carried by a bottom wall or floor 15, are adapted to removably engage.

The brooder has flexible felt side walls 16 secured by fastening members 17 to the opposite longitudinal edges of the top wall 10. The side walls 16 have openings 16a by means of which

2

the chicks can enter or leave the brooder when the side and end walls are down. End felt walls 18 are also formed integral with the side walls 16 so that a felt side wall structure is provided by means of which the small chicks may readily enter the interior of the brooder structure.

The side walls 16 adjacent the lower portions thereof are formed with flaps 19 and the end walls 18 may also be formed with similar flaps. 10 These flaps 19 are provided so that the chicks may push the flaps inwardly in order to gain entrance into the interior of the brooder.

The side and end walls 16 and 18 respectively overlap the bottom 15 and may be secured by 15 buttons 20. The felt side and end wall structure is adapted to be raised in warm weather and held in raised position by means of buttons 20, or other suitable means, which may be secured to the side walls 16. The lower portions of the side 20 walls are formed with button holes 22 for engagement with the buttons 20 in order to hold the flaps and the lower portions of the felt side wall structure in raised position.

A handle 21 is secured to the top wall 10 and 25 provides a means whereby the brooder can be shifted from place to place.

The top wall 10 has secured to the inner or lower side thereof an inner felt member 23. The felt member 23 has dependently secured thereto 30 a plurality of felt strips 24 which depend within the interior of the brooder and between which the chicks are adapted to engage. A copper plate 25 is interposed between the felt 23 and the lower side of the top wall 10.

35 A lower felt wall 26 is disposed on the upper side of the bottom wall 15 and a lower copper plate 27 is interposed between the felt 26 and the upper side of the bottom wall 15.

The lower felt 26 is preferably removable from 40 the bottom wall, in order to provide for cleaning thereof, and the outer corner portions of the felt 26 are interposed between the lower ends of the supporting posts 11 and the upper side of the bottom wall 15. The bottom wall 15 is detachably 45 secured to the lower ends of the posts 11 by means of hooks 28 which are secured to the posts 11 and which engage eyes 29 carried by the bottom wall 15, there being a set of such hooks and eyes for each post.

50 A brooder has been constructed according to this invention and has been found to simulate more closely the body heat of the mother hen. With a construction of this kind it is not necessary to provide any artificial heating means to keep the chicks warm.

In the construction of the brooder for best results the copper plates should be very thin. The strips of felt hanging from the ceiling of the brooder should clear the floor by about one-half inch. Securing the floor in the manner specified makes it easy to carry the brooder as a unit from place to place. To clean and keep the brooder sanitary, the hooks can be released and the top structure lifted off. The floor sheet of felt can then be easily removed, cleaned and turned, if desired. The chicks make their own heat and those in the center who get too warm can move to the outside while those on the outside who may feel too cool can move towards the center. With this brooder all hazards of loss from under heating, fire, gas or explosions are eliminated, and the chicks raised are sturdier, healthier and will feather out more quickly and uniformly.

The legs for a chicken brooder must be six inches but for turkey chicks the legs can be longer, say from eight to ten inches, if desired.

What I claim is:

A brooder comprising a housing formed of top

and bottom walls, corner posts for supporting said top wall above said bottom wall, upwardly extending pins carried by said bottom wall, said posts having sockets for receiving said pins, eyes carried by said bottom wall, hooks carried by said posts for releasably holding said posts on said pins, felt side and end walls about said posts, each of said side walls having at least a pair of upwardly extending slots of sufficient size to provide chick entrances and the portions of the walls between the slots on each side providing a swinging flap, means releasably securing said side and end walls to said bottom wall, means carried by said side walls for holding said flaps in raised position, a copper plate secured to the lower side of said top wall, a second copper plate secured to the upper side of said bottom wall, a felt covering for said upper plate, depending felt strips carried by said upper felt covering, and a lower felt covering for said lower plate.

HARVEY L. CLARK.
